UNITED STATES PATENT OFFICE.

FRANK M. VOGAN, OF CANTON, OHIO, ASSIGNOR TO THE DICELMAN MANUFACTURING COMPANY, OF FOREST, OHIO, A CORPORATION OF OHIO.

DESIGN FOR A ROOFING-TILE.

41,799.

Specification for Design.

Patented Sept. 19, 1911.

Application filed June 14, 1911. Serial No. 633,207. Term of patent 7 years.

To all whom it may concern:

Be it known that I, FRANK M. VOGAN, a citizen of the United States, residing at Canton, in the county of Stark and State of Ohio, have invented a new, original, and ornamental Design for a Roofing-Tile, of which the following is a specification, reference being had to the accompanying drawing, forming part thereof.

The drawing illustrates a plan view of a roofing tile, showing my new design.

I claim:

The ornamental design for a roofing tile as shown.

FRANK M. VOGAN.

Witnesses:

WILLIAM H. MILLER,
IRENE LUTZ.
